CLAIM

[21] Appl. No.: 737,858

The ornamental design for a chair base or similar article, as shown and described.

[22] Filed: May 28, 1985

DESCRIPTION

[30] Foreign Application Priority Data

FIG. 1 is a perspective view of a chair base or similar article, showing my design;

FIG. 2 is a perspective view of a chair base, showing a second embodiment of my design;

FIG. 3 is a perspective view of a chair base showing a third embodiment of my design; and,

FIG. 4 is a perspective view of a chair base showing a fourth embodiment of my design.

The chair base forms are generally symmetrical about a vertical axis while the undisclosed bottom surfaces are unadorned.
